A. H. Spencer,

Clothes Winger.

No. 22364.

Patented Feb. 1, 1870.

Witnessed,

David A. Hunt.
Henry A. Marshall.

Inventor,
Albert H. Spencer.

United States Patent Office.

ALBERT H. SPENCER, OF PROVIDENCE, RHODE ISLAND.

Letters Patent No. 99,364, dated February 1, 1870.

IMPROVED CLOTHES-WRINGER.

The Schedule referred to in these Letters Patent and making part of the same.

I, ALBERT H. SPENCER, of Providence, in the county of Providence, and State of Rhode Island, have invented certain Improvements in Wringing-Machines, of which the following is a specification.

Nature and Objects of the Invention.

The first part of my invention relates to a curved clamp, which, in combination with a thumb-screw at each end, is capable of securing the wringer to a tub; the object of this part of my invention being to provide an elastic clamp, adapted to attach the wringer firmly to tubs of various sizes and thicknesses.

The second part of my invention relates to a journal-cap or bearing, arranged to regulate the movement of the springs and rollers, and confine them within specified limits.

The third part of my invention relates to a double inclined water-shed, beneath the rollers, arranged to discharge the expressed water from either side of the machine at pleasure.

Description of the Accompanying Drawings.

Figure 1 is a perspective view of a machine embodying my inventions.

Figure 2 is a horizontal section through the machine, at the centre of the curved clamp.

Figure 3 is a perspective view of the journal-cap, showing also the position of the spring.

Figure 4 is a vertical section of the rollers and water-shed, showing their relative position.

General Description.

A and B are the rubber rollers, between which the articles to be wrung are passed, when the rollers are rotated by the crank and gears.

The roller B has a fixed bearing in the upright pieces of the frame C C, while the upper one is free to rise and fall within certain limits, its bearings being the journal-caps D D.

Pressure is applied to the springs E F by means of the thumb-screw G, (which passes through F, and the screw-plate H, attached thereto,) and has the effect to separate the springs more widely when power is applied.

A rubber spring is inserted at I, between F and the upper cross-piece J.

K is the water-board, for conveying the expressed water into a tub on either side.

L is the curved clamp, for attaching the machine to a tub, and is operated by the screws m m.

N N are thin plates of metal, attached to the clamp L, to aid in withdrawing it.

O is a thin strip, at the apex of the water-shed K, to direct the water into the proper tub.

P is the upright part of the bench, to which the wringer is attached;

Q, the platform of the same;
R R, the hinges; and
S S, the cross-pieces.

In adjusting my wringer to a tub, I use the clamp L, which is curved on its inner face to about the shape of the side of a medium-sized tub, forming thus an arc of a circle, of about twenty-three inches diameter. I give to this clamp sufficient elasticity to adapt it to tubs of various sizes, by making it thin near its central part, and apply pressure near its ends by the screws m m, causing it to clasp the tub firmly. The points of these screws are provided with heads, which work behind pins or plates of metal, N, attached to the clamp, so that a reverse motion of the screw relieves the pressure on the tub, and withdraws the clamp.

By introducing the head of this screw to its position through a recess in the end of the clamp, the plates N N could be dispensed with.

I am aware that a patent has been granted to a Mr. Glass, for a curved clamp, in combination with various other devices; but my aim is to provide a simple elastic clamp, receiving a positive motion, both forward and backward, from the screws m m.

In the operation of wringing, the pressure of the springs E F is communicated to the rollers through the bearing-blocks D D, the spring E taking the position shown in dotted lines in fig. 3.

The outer face of this block is extended upward, almost to the upper spring, to regulate the motion of the lower spring, preventing it from lateral displacement, and also from rising beyond a specified point. This portion of the journal-block is marked D'. This limitation serves also to prevent so great separation of the rolls as to disconnect the cogs. I use this bearing at one or both ends, at pleasure.

It is customary, in some wringers, to attach, beneath the rollers, a sloping board or spout, to carry again to the tub the water expressed from an article being wrung. These boards discharge only one way, always into the same tub, until the machine is removed to another. I remedy this defect, and enable the operator to wring from either of two adjacent tubs, discharging the waste water into either tub at pleasure, by making this water-shed slope both ways from the under surface of the lower roller. This is of very great importance in such machines as are used on stationary tubs, set side by side, or in those used on my improved wringer-bench, where the tubs always occupy a certain position adjoining each other.

This water-shed, being fixed and permanent, requires no adjusting, the water being always expelled on that side from which the wet clothes are received, whether front or rear.

I find it an advantage to insert, at the apex of this double inclined board, a strip of leather, sheet-rubber, packing, or other material, projecting just enough to

graze the under surface of the roller, as at O, fig. 4, and more surely discharge the water on the side on which it is expressed.

I claim, as my invention—

1. The improvement in clothes-wringers herein described, consisting of the elastic curved clamp L, in combination with the headed screws m, by which the clamp may be tightened or loosened, for the purposes set forth.

2. The improvement, herein described, in the means for preventing the disconnection of the cog-wheels,

consisting of the journal-block D, provided with its upward-projecting member D', the same being arranged with relation to the springs E and F, in the manner and for the purposes set forth.

3. In combination with the double inclined watershed K, the intermediate strip O, constructed as and for the purposes described.

ALBERT H. SPENCER.
